UNITED STATES PATENT OFFICE.

WILLIAM E. HUGHES AND JAMES B. KING, OF CLYDE, OHIO, ASSIGNORS TO THE HUGHES GRANITE COMPANY, OF CLYDE, OHIO, A CORPORATION OF OHIO.

MAUSOLEUM CONSTRUCTION.

1,342,812.

Specification of Letters Patent.

Patented June 8, 1920.

Application filed November 21, 1917. Serial No. 203,265.

To all whom it may concern:

Be it known that we, WILLIAM E. HUGHES and JAMES B. KING, citizens of the United States, residents of Clyde, county of San-dusky, and State of Ohio, have invented new and useful Improvements in Mausoleum Constructions, of which the following is a specification, the principle of the invention being herein explained and the best mode in which we have contemplated applying that principle, so as to distinguish it from other inventions.

Our invention relates to mausoleum constructions which are designed for the reception of a plurality of bodies and particularly to an economical and permanent construction thereof and to the ventilating and drainage systems of such constructions. The invention is designed to provide a sightly, economical and permanent structure and to ventilate and drain the walls, lobbies and crypts of such constructions in a much more thorough and satisfactory manner than in any previous construction of which we are aware. Our invention effectively secures sanitary desiccation of bodies by natural means without the necessity of using any disinfecting material except possibly in special instances, as hereinafter fully explained.

The annexed drawings and the following description set forth in detail certain means embodying our invention, the disclosed means, however, constituting but one of various mechanical forms in which the principle of the invention may be employed.

In said annexed drawings:

Figure 1 represents a transverse vertical section of our improved mausoleum, taken in the plane indicated by the lines I—I, Fig. 3; Fig. 2 represents a horizontal section, taken in the plane indicated by the lines II—II, Fig. 1; Fig. 3 represents a horizontal section taken in the planes indicated by the lines III—III, Fig. 1; Fig. 4 represents a longitudinal vertical section taken in the plane indicated by the lines IV—IV, Fig. 2; and Fig. 5 represents a perspective elevation and section, upon an enlarged scale, of an improved form of ventilator and moisture-eliminating means forming part of our improved mausoleum structure.

In said annexed drawings, there is indicated a granite, marble, stone or other suit-

able wall construction for our improved mausoleum comprising the front wall 1, the rear wall 2 and the side walls 3, surmounted by a top member 4 constructed of one or more pieces, as desired, the whole being 60 suitably supported upon a concrete or other suitable foundation, as shown. The roof 4 is a locking device that ties the whole building together. Said wall and top construction is formed of granite or other blocks 65 interlocked in the manner suggested in the accompanying drawings, the detail of which forms the subject-matter of our pending application for U. S. Letters Patent upon wall constructions for mausoleums, Serial 70 No. 203,266. In the rear wall 2 is formed a window opening 29 connected by upper and lower channels 30 with the atmosphere adjacently the top and bottom of a lobby 5 and formed with openings 30', shown in 75 Figs. 1 and 2, communicating with opening 29, the whole being shown in detail and forming the subject-matter of our pending application for U. S. Letters Patent on devices for preventing moisture deposit on 80 windows, Serial No. 203,264.

There is provided in our improved mausoleum a series of superimposed inclosed crypts 7, there being shown in the exemplification of our invention illustrated in the 85 accompanying drawings two oppositely disposed series of such crypts separated by the lobby portion 5, an entrance to the latter of which is afforded in the front of the structure through the door 6. The floor of 90 the lobby is indicated by the ordinal 8. The ceiling of the lobby is indicated by the ordinal 16 supported upon the members 15 forming the top of the uppermost crypts 7 and above the opening 15' formed between 95 said members 15, member 16 being formed in its rear end wall with openings 16' communicating with the upper channel 30 and thence to the atmosphere. Between the structure top 4 and the members 15 and 16 100 is formed a space 9, exit from which to the atmosphere is afforded through the openings 10 in the side walls 3. As described in United States Letters Patent No. 949,771, issued to ourselves and Frank W. Hall, the 105 inclosed receiving crypts 7 are independently ventilated, being provided, respectively, with air inlet openings 11 and outlet openings 12, said inlet openings 11 being located in one side of the crypt and the 110

outlet openings 12 being located in the opposite side of the crypt, the outlet openings being located in a horizontal plane near the top of the crypts and the inlet openings being located in a horizontal plane near the bottom of the crypts. Said inlet openings 11 communicate with chambers 13, which in turn communicate through wall openings 14 with the atmosphere. Said outlet openings 12 communicate with the space 9.

Other openings 17 in the side walls 3 communicate with ducts 23 formed between the front, rear and side walls and the ends and rear of the crypts 7, which ducts 23 in turn communicate at their upper ends with the atmosphere through openings 18 in the side walls 3. There is provided in the floor 8 of the lobby a floor ventilator 19 connected by pipe 19' with a chamber 24 communicating with the atmosphere in the rear of the mausoleum through an opening 24', said chamber 24 being drained through a duct 19² to the main drain 26 of the mausoleum structure. Said drain 26 also receives through ducts 25 any water of condensation formed in the ducts 23 between the walls and crypts. The opposite openings provided in the walls, crypts and lobby, as described, create a natural draft which results in a continuous current of air therethrough. The drainage from the crypts 7 is effected by means of ducts 20, the upper ends of which are connected to the bottoms of said crypts, and the lower ends of which are connected with a common trap or pipe 21 located below the surface of the ground and between the foundation walls; thence through a duct 22 leading downward and outward this drainage is discharged into the ground at the rear of the mausoleum structure and at a desirable distance below the surface of the ground, as plainly shown in Fig. 3. This system of drainage from the crypts takes care of all moisture therein arising from dropsical bodies and other sources and absolutely prevents any untoward conditions existing by reason of the backing up of any foul gases or the intercommunicating of the moisture from two or more crypts. In special instances it may be advisable to provide disinfecting material in connection with the desiccation of one or more bodies and it will be noted that our construction providing for independent ventilation and drainage of the separate crypts allows such material to be used for such crypts and bodies as is desired. Such disinfecting would be effected in connection with the lower air chambers 13 or other suitable space without affecting the interior of the mausoleum. The chambers 13 are drained by means of pipes 27 into the main drain 26. If any drainage of the upper air chamber 9 is required, we have provided 60 for the same by means of the ducts 23' lead-

ing into the ducts 23, as plainly shown in Fig. 1. Except for the openings 17 and 18 and the openings in the ducts 23' and 25, the ducts 23 are completely sealed. Ventilators 28 are provided for each of the wall openings 10, 14, 17 and 18 and for the rear foundation opening 24'. We prefer to construct the ventilator provided in these wall openings of a plurality of screens constructed and disposed as shown in Fig. 5, 75 wherein three screens 28', 28² and 28³, are provided in each of said openings, said screens being of different mesh, screen 28' of largest mesh and provided with the well-known weather strip 28⁴ being disposed 80 nearest the outer end of the opening, screen 28² of intermediate size mesh being disposed intermediately screen 28' and screen 28³, the latter being of smallest mesh. This construction effectively prevents the blowing of 85 rain or moisture through the wall openings inasmuch as the outer screens baffle and break up the water and in connection with the inner screen entrain the same so that only a slight amount of moisture from this 90 source enters the mausoleum, thus satisfactorily eliminating precipitation in the building.

By the construction hereinbefore described, it will be noted that we have provided separate and independent systems of ventilation and of drainage for the interior of the walls, each separate crypt, and the lobby. Particular attention is directed to the satisfactory ventilation and drainage 100 effected between the walls and crypts. Furthermore, we have provided by means of the drain portions 27 means for any necessary draining of the chambers 13. As described and claimed in detail in our pending application for U. S. Letters Patent on wall constructions for mausoleums, Serial No. 203,266, we have provided the inner surface of the side and end walls with a mastic coating to form a smooth surface, 110 over which is applied a sizing coat to form an air and moisture proof surface. Our invention results in a very satisfactory ventilation and drainage of all parts of the mausoleum, preventing putrefaction of the 115 contained bodies and providing for the sanitary desiccation thereof by reason of the elimination of bacteriological propagation which requires moisture.

What we claim is:

1. In a mausoleum, the combination with suitable side and end walls, a series of enclosed receiving crypts, and a roof, said series of crypts being removed from said walls to form an air space therebetween, said 125 latter space communicating with the atmosphere near its top and bottom, a main drain disposed beneath the ground and around the mausoleum structure, a drainage duct connecting the bottom of said wall 130

space with the said main drain, a drainage duct connecting the bottom of each crypt with a trap drain positioned below the ground and between the foundation walls,

5 and a duct connected with said trap drain leading downward and outward for discharging its drainage into the ground at the rear of the mausoleum structure and at a suitable distance below the surface of the

10 ground.

2. In a mausoleum, the combination with suitable side and end walls, a series of superimposed inclosed crypts, a roof and a lobby, said series of crypts being removed
15 from said wall so as to form an air space therebetween, a main drain disposed beneath the ground and around the mausoleum

structure, a drainage duct connecting the bottom of said wall space with said main drain, a drainage duct connecting the bottom of the lobby with said main drain, a drainage duct connecting the bottom of each crypt with a trap drain positioned below the ground and between the foundation walls of the structure, and a drainage duct
20 connected with said trap drain leading downward and outward for discharging its drainage into the ground at the rear of the mausoleum structure and at a suitable distance below the surface of the ground. 25

Signed by us, this 10th day of Nov., 1917. 30

WILLIAM E. HUGHES.

JAMES B. KING.
